UNITED STATES PATENT OFFICE

HERMAN E. WINTERHOFF, OF INDIANAPOLIS, INDIANA, ASSIGNOR TO LEEDY MANUFACTURING COMPANY, OF INDIANAPOLIS, INDIANA, A CORPORATION OF INDIANA

MUSICAL ELEMENT

Application filed December 4, 1929. Serial No. 411,535.

The object of my invention is to produce a new musical instrument, or implement, of the percussion type and of such character that a musical sound of pleasing character and desired pitch and volume may be produced, the new implement or instrument comprising much less material than has heretofore been required to produce an element capable of producing a somewhat similar sound of the same pitch and volume.

A musical instrument, of any desired range, may be produced by placing in desired proximity a proper number of my new elements which have been properly pitched.

15 My new element is composed of a tubular section of resonant material to which is rigidly secured a laterally extending vibratory reed or bar of resonant material the reed or bar being so proportioned as to length and thickness (thereby determining its pitch responsive to percussion) that when firmly secured to the tube, the unit will, when struck, emit a sound the pitch of which is such that the air column defined by the tube will be set 25 into resonant vibration, the percussion pitch of the unit being preferably the same as the resonating pitch of the tube.

The accompanying drawings illustrate my invention in various aspects.

30 Fig. 1 is a section of one form of my invention medially of both bar and tube, the end of the tube most remote from the bar being open; Fig. 2 a similar section of another form in which the bar end of the tube is open and the far end closed; Fig. 3 a similar view of another form where both ends of the tube are open; Fig. 4 a similar view of another form in which two tubes are attached to opposite faces of the bar; Fig. 5 a similar view of another form in which an open-ended tube is projected through the bar; Fig. 6 a similar view of another form in which the tube is attached to one face of a bar of twice the vibrating length of the bar shown in the other figures; Fig. 7 a medial section of a modifica-

tion capable of producing a fuzzy, jazzy tone, and Fig. 8 a perspective of a group of my new elements.

In the drawings 10 indicates a tube of resonant material the length of which will provide an air column of such length that, when set into vibration, a tone of the desired pitch will be produced. Such tubes have heretofore been commonly used as resonators and the method of determining the requisite length for a resonator tone of desired pitch is well known. For convenience I shall at times refer to the tone pitch of the air column of the tube as the resonator pitch of the tube. This tube must be of such material as to be capable of producing a clear tone under percussion and preferably may be of brass or bell metal such as is commonly used in tubular chimes although other resonant material, such as hard wood, say cocobolo, will in some combinations, give pleasing and satisfactory results.

Rigidly secured to tube 10 is a vibratory reed or bar 11 of resonant material capable of producing a clear tone under percussion. If the tube 10 is metal the bar 11 should preferably be metal and, like tube 10, the metal should be such as to emit a musical tone of reasonably resonant qualities. For instance, a soft metal like lead would not 75 be useful for either tube or bar. The attachment of bar 11 to tube 10 must be of such character that the two bodies will vibrate as a unit under percussion.

As is well known, the resonator pitch of a tube is dependent upon its length, and a tube closed at one end has a resonator value equal to that of a tube of twice the length but open at both ends.

It is, of course, well known that the pitch 85 of the fundamental tone response of a percussed relatively short tube, of a given diameter and wall thickness is independent of the length of the tube because this tone pitch is due to diametrical oblations of the tube wall. 90

This tone pitch of the tube may be conveniently called its percussion pitch. It is also well known that the tone pitch of resonant flat bars is a function of length and thickness and is independent of width. It is therefore readily possible with bars of given thickness and material to calculate the length required, when supported at or near its primary nodes, to give a tone of given pitch under percussion. This pitch may be conveniently referred to as the percussion pitch of the bar.

The fundamental characteristic of my new musical element is that the tube and bar, under percussion vibrate as a whole to produce a tone the pitch of which is such as to develop the resonator tone of the tube.

While I am not able at this time to announce any mathematical formula by which the length, thickness and width of bar required for proper coordination with the resonator and percussion values of the tube, I shall state a few comparative dimensions which will indicate the general principles which underlie production of my devices.

The bar is preferably secured to the tube as shown in Fig. 1 where the major portion of the length of the bar is substantially to one side of the axis of the tube and the bar forms a closure for one end of the tube. The tube may, if desired, be secured at one end of the bar with no projection but a slight projection, as indicated in Fig. 1, is convenient to permit supporting the element with the bar horizontal and the tube depending.

Using thin wall tubes, the lengths of which were proper to give resonator pitches of A, B, C and D above middle C, bars $\frac{1}{6}$ " thick and having widths closely approximating the selected tube diameters, gave, under percussion, the tones C, C $\sharp$, D $-$ and D $+$ respectively, in the octave above middle C, as indicated below:

Again, with thin wall tubes, as above, and bars $\frac{1}{8}$ " thick giving the same ultimate resonated percussion tones, the bars alone, under percussion, were pitched in the octave above middle C, respectively A $\sharp$, C $-$, C $+$ and C $\sharp$, as follows:

65 With tubes having walls about double the

thickness of the tubes mentioned above, and with $\frac{1}{8}$ " bars the bars alone, under percussion, were pitched in the octave above middle C respectively A $\sharp$, B $+$, C $-$ and C $\sharp$, as follows:

The tubing, used above, was brass, $1\frac{1}{2}$ " inch external diameter, the thin tubing being 22 B. & S. gauge and the thick 14 B. & S. gauge, the percussion pitches of which were respectively A in the second octave above middle C and D in the fourth octave above middle C.

My new element must be so supported as to be free to vibrate as a unit and there are several ways in which proper support may be given. For instance the bars may rest upon a pair of parallel felt strips 15, or strings spaced apart slightly more than the tube diameter, with the tube depending between them. The lateral spacing need not be very accurate except that one support should not be too near to the free end of the bar. The tubes may, if desired extend upwardly. The element may be also suspended by a cord, by threading through a hole, or otherwise, from most any point in the length of either tube or bar, except quite close to the free end of the bar, so long as the unit as a whole is free to vibrate under percussion.

Satisfactory tone quality may be produced by applying percussion at any point in the length of the tube or bar, though the best results appear to be obtained by striking the bar either in line with the tube or close to its free end. There appears to be a node in the bar about midway between its free end and the tube axis and if the bar is struck at or near this node the resonance is damped.

In the form shown in Fig. 2 the open end of the tube 10 is secured in a perforation in the bar 11, the other end of the tube being closed by a cap 12. In Fig. 3 the tube 10, being open at both ends with one end secured in a perforation in the bar, as in Fig. 2, must be twice as long as the tubes in the forms shown in Figs. 1 and 2, the desired resonated percussion pitch being the same. In Fig. 4, two tubes 10 with their adjacent ends closed by the intervening bar 11, are shown, and in Fig. 5 a continuous tube, open at both ends, is passed through a perforation in bar 11. Of these last two forms, the one shown in Fig. 4 appears to be the better but neither is better than the forms shown in

Figs. 1 and 2, and, as more material is used, they appear to be less desirable commercially.

In the form shown in Fig. 6 tube 10 is applied to the middle of a bar 11 of twice the vibrating length of the bar 11 in the other figures. There are some difficulties in tuning this structure and, as it too requires considerably more material than the forms shown in Figs. 1 and 2, it appears to be less desirable commercially.

Jazzy, or fuzzy effects, may be obtained by closing one end of the tube with a loosely retained diaphragm 14, as indicated in Fig. 7, the other end being left open.

No effort has been made, in the drawings, to show accurate relative proportions of bars and tube, except only to indicate the fact that if a tube open at both ends is used such tube must be twice the length of a tube which is closed at one end.

The most sonorous results seem to be attained with relatively thin gauge tubing and thin bars, the thickness of the bars being sufficient to provide reasonable length.

I claim as my invention:

1. A musical instrument of the percussion type composed of a tube and a bar each of resonant material and rigidly directly connected so as to vibrate as a unit under percussion, said bar being so proportioned as to its percussion pitch, relative to the resonator pitch and percussion pitch of the tube, that the percussion pitch of the unit will be the same as the resonator pitch of the tube.

2. A musical instrument of the percussion type composed of a tube of resonant metal and a bar of resonant metal rigidly directly connected so as to vibrate as a unit under percussion, said bar being so proportioned as to its percussion pitch, relative to the resonator pitch and percussion pitch of the tube, that the percussion pitch of the unit will be the same as the resonator pitch of the tube.

3. A musical instrument of the percussion type composed of a tube and a bar each of resonant material and rigidly directly connected so as to vibrate as a unit under percussion, said bar being so proportioned as to its percussion pitch, relative to the resonator pitch and percussion pitch of the tube, that the percussion pitch of the unit is such that the air column within the tube will be set into resonating vibration by percussion on the tube or bar.

4. A musical instrument of the percussion type composed of a tube of resonant metal and a bar of resonant metal rigidly directly connected so as to vibrate as a unit under percussion, said bar being so proportioned as to its percussion pitch, relative to the resonator pitch and percussion pitch of the tube, that the percussion pitch of the unit is such that the air column within the tube will be

55 set into resonating vibration by percussion on the tube or bar.

5. A musical instrument of the percussion type composed of a tube and a bar each of a resonant metal rigidly secured directly together by application of the bar as a closure for one end of the tube, so that the tube and bar will vibrate under percussion as a unit, said bar being so proportioned as to its percussion pitch, relative to the resonator pitch and percussion pitch of the tube, that the percussion pitch of the unit is such that the percussion pitch of the unit will be the same as the resonator pitch of the tube.

6. A musical instrument of the percussion type composed of a tube and a bar each of a resonant material rigidly secured directly together by application of the bar as a closure for one end of the tube, so that the tube and bar will vibrate under percussion as a unit, said bar being so proportioned as to its percussion pitch, relative to the resonator pitch and percussion pitch of the tube, that the percussion pitch of the unit is such that the percussion pitch of the unit will be the same as the resonator pitch of the tube.

7. A musical instrument of the percussion type composed of a tube and a bar each of a resonant metal rigidly secured directly together by application of the bar as a closure for one end of the tube, so that the tube and bar will vibrate under percussion as a unit, said bar being so proportioned as to its percussion pitch, relative to the resonator pitch and percussion pitch of the tube, that the percussion pitch of the unit is such that the percussion pitch of the unit will be the same as the resonator pitch of the tube.

8. A musical instrument of the percussion type composed of a tube and a bar each of a resonant material rigidly secured directly together by application of the bar as a closure for one end of the tube, so that the tube and bar will vibrate under percussion as a unit, said bar being so proportioned as to its percussion pitch, relative to the resonator pitch and percussion pitch of the tube, that the percussion pitch of the unit is such that the air column within the tube will be set into resonating vibration by percussion of the tube or bar.

9. A musical instrument of the character specified in claim 1 wherein one end of the tube is closed by a loosely retained diaphragm.

10. A musical instrument of the character specified in claim 2 wherein one end of the tube is closed by a loosely retained diaphragm.

11. A musical instrument of the character specified in claim 3 wherein one end of the tube is closed by a loosely retained diaphragm.

12. A musical instrument of the character

specified in claim 4 wherein one end of the tube is closed by a loosely retained diaphragm.

In witness whereof, I have hereunto set my hand at Indianapolis, Indiana, this 29th day of November, A. D. one thousand nine hundred and twenty-nine.

HERMAN E. WINTERHOFF.
